LUMINAIRE REFRACTOR

William F. Little, Yonkers, N.Y., and Vearl S. Wince, Newark, Ohio, assignors of one-half to Holophane Company, Inc., New York, N.Y., a corporation of Delaware, and one-half to Electrical Testing Laboratories, Inc., New York, N.Y., a corporation of New York

Filed Oct. 21, 1965, Ser. No. 87,658

Term of patent 14 years

(Cl. D48—16)

FIG. 1 is an elevational view of the luminaire refractor of the invention, partially broken away to show the internal design in elevation, the exterior and internal design on the right and left sides respectively of the figure being the same as shown on the left and right sides, respectively, thereof;

FIG. 2 is a quadrant of a top plan view of the luminaire refractor, the remaining quadrants having a repeat pattern as shown; and

FIG. 3 is a quadrant of a bottom plan view of the luminaire refractor, the remaining quadrants having a repeat pattern as shown.

We claim:

The ornamental design for a luminaire refractor, as shown and described.
